UNITED STATES PATENT OFFICE.

JOHN MARTIN YANIGLOS, OF NORTHAMPTON, PENNSYLVANIA.

STORM BOOT.

Application filed March 16, 1920. Serial No. 366,414.

To all whom it may concern:

Be it known that I, JOHN M. YANIGLOS, a citizen of Austria-Hungary, now Czechoslovakia, residing at Northampton, in the county of Northampton and State of Pennsylvania, have invented new and useful Improvements in Storm Boots, of which the following is a specification.

This invention relates to boots and has for an object the provision of a boot which is of a strong and durable construction, being especially designed for rough wear and which may be manufactured at a nominal cost.

Another object of the invention is the provision of a boot, the upper of which is made of leather, or similar tough material and the leg of heavy cloth, so as to afford protection to the leg, novel means being provided for connecting the leg and upper to insure a strong and durable boot.

Another object is the provision of means for constructing the top portion of the leg so as to fit snugly about the leg of the wearer, in order to keep out snow or rain.

With the above and other objects in view, the invention further includes the following novel features and details of construction, to be hereinafter more fully described, 30 illustrated in the accompanying drawings and pointed out in the claim.

In the drawings:—

Figure 1, is a perspective view of a boot embodying the above invention.

Figure 2 is a rear elevation of the same.

Referring to the drawings in detail, wherein like characters of reference denote corresponding parts, the boot comprises an upper 10, which is preferably formed of leather or similar tough material, having secured thereto a relatively heavy sole 11 and heel 12.

The leg portion of the boot indicated at 13, is preferably made of heavy cloth, the front and rear portion of the leg being formed separately and secured together along each side at the point indicated at 14. In order to secure the upper and leg together in a strong and durable manner, 45 the upper is formed upon opposite sides

with a tongue 15, and at the front with the tongue 16. These tongues extend upward along the boot leg, to which they are secured by stitches 17, while a row of stitches 18 extends around the top portion of the upper, a tongue 19 is also provided at the rear or heel portion of the boot, but the tongue is separately formed so as to provide a re-enforcing strip which extends from the upper portion of the heel and along the back of the upper and the rear portion of the leg, to which it is secured by stitching as at 20. To provide for conveniently removing the boot, the heel portion has secured thereto a leather triangular shaped toe piece 21, which may be engaged with the sole of the other boot or with the boot strap to aid in removing the boot.

The top edge of the leg is provided with a re-enforcing binding 22, the latter extending entirely around the top of the leg portion which is slotted as shown at 23. Located upon one side of the slit and secured to the leg is a buckle 24, while secured to the leg from the opposite side of the slit is a strap 25. By this means the top of the leg may be fastened tightly about the leg of the wearer so as to prevent the entrance of rain or snow into the top of the boot.

The invention is susceptible of various changes in its form, proportions and minor details of construction and the right is herein reserved to make such changes as fall within the scope of the invention.

Having described the invention what is claimed is:—

A boot comprising a leather upper, a plurality of spaced upwardly extending tongues formed integrally therewith, and said tongues being arranged progressively at right angles with respect to each other, a fabric leg portion secured to the upper edge of said upper and the edges of each tongue respectively, an auxiliary row of stitching following the upper edges of said upper but below the bottom portion of the tongues, means for adjusting the size of the upper end of the fabric leg portion, a binding secured around the upper edge of said leg

portion for the purpose of re-enforcing that part thereby, a heel secured to the bottom of said upper, a sole secured to the bottom of said upper and engaging the heel, a separate tongue disposed above the rear of the heel and secured to said upper and leg portion respectively, and a leather toe piece

triangle shape in outline rigidly secured upon the last mentioned tongue with one of its sides uppermost for the purpose specified. 10

In testimony whereof I affix my signature.

JOHN MARTIN YANIGLOS.
